Inventor

W.S.Tedder

Lacy Keagy, Attorney

UNITED STATES PATENT OFFICE.

WILLIAM SEABORN TEDDER, OF OLA, ARKANSAS.

BROOMCORN CLEANER.

Application filed May 14, 1924. Serial No. 713,272.

To all whom it may concern:

Be it known that I, WILLIAM S. TEDDER, a citizen of the United States, residing at Ola, in the county of Yell and State of 5 Arkansas, have invented certain new and useful Improvements in Broomcorn Cleaners, of which the following is a specification.

This invention is a device for cleaning 10 broom corn and has for its object the provision of a simple and inexpensive device by the use of which the seeds, particles of dirt and other impurities may be readily stripped from a bunch of corn. The invention 15 is illustrated in the accompanying drawing and will be hereinafter fully described, the novel features being particularly pointed out in the appended claim.

In the drawing:

20 Figure 1 is an elevation, partly broken away and in section, of a device embodying my invention, and

Fig. 2 is a transverse section on the line 2—2 of Fig. 1.

25 In carrying out my invention, I employ a standard 1 which may be secured to any convenient fixed support or base. This standard is formed at its upper end to provide an open space between side posts or 30 extensions 2 and in the lower wall of the said space or opening is a slit or groove, indicated at 3. Secured in any convenient manner within the said slit or groove is a lower stripping plate 4 which projects into the lower portion of the open space and has 35 its upper edge provided with teeth 5, as clearly shown in Fig. 1. The side extensions 2 are slotted, as shown at 6, and in the said slots are received the ends of an upper stripping plate 7, the lower edge of which is formed with teeth 8 mating with the teeth 5 of the lower stripping plate. A handle or gripping member 9 of any convenient form 40 is secured to the upper stripping plate along the upper portion thereof between the side extensions 2 and the ends of this handle or gripping member, coacting with the inner walls of the said extensions, serve as guides in the movement of the plate. The plate is 45 further guided by the side walls of the slots 6, as will be readily understood. The end portions of the upper stripping plate project through the slots 6 into similar alined slots formed in wings 10 which are secured to or 50 formed upon the side edges of the standard

1 and the said wings are provided with grooves 11 in the opposed walls of their vertical slots, which grooves merge into sockets 12 in the wings below the slots. Coiled 60 springs 13 are seated in the said sockets and in the lower portions of the said grooves and bear against the lower edge of the upper stripping plate 7 adjacent the ends thereof, as clearly shown in Fig. 1. Stop members 65 14 of any preferred form are secured across the upper ends of the slots 6 so that the upward movement of the upper stripper plate may be limited.

In assembling the parts, the lower stripping plate is secured permanently within the standard 1 at the base of the opening through the upper end thereof, as shown. The springs 13 are then dropped into the 70 sockets 12 of the wings or side members 10 and the upper stripping plate is then inserted in the upper portions of the slots 6 and into the slotted portions of the said wings so that the ends of the said stripping plate will rest upon the springs 13. The 75 stop members or other closures 14 may then be secured in place.

In using the device, the upper stripping plate is permitted to assume its upper position in spaced relation to the lower stripping plate, and a bunch of broom corn is inserted 80 at its head end between the two stripping plates. The upper stripping plate is then pressed downwardly to bear upon the bunch of corn so as to spread the same and exert sufficient pressure thereon to yieldably hold 85 it without cutting through it. The corn is then drawn by hand through the space between the opposed edges of the stripping plates and the teeth on the plates will strip 90 therefrom all seeds, particles of dirt and other matter which may be adhering thereto. At the same time the bunch will be spread somewhat so that it will be brought 95 into proper form for use in a broom head. My device is obviously exceedingly simple 100 in construction and may be produced at a very low cost.

Having thus described the invention, I claim:

A broom corn cleaner comprising a 105 standard having vertically slotted extensions at its upper end, a stripper plate secured in the standard and extending across the space between the said extensions, said plate being provided with teeth along its 110

upper edge; wings on the sides of the standards at the upper end thereof and provided with vertically extending slots and sockets at the base of the said slots, coiled springs seated in said sockets and extending into said slots, an upper stripper plate engaged freely through the slotted extensions

of the standard and in the slots of the said wings, said plate being provided with teeth along its lower edge, and stop members across the slots in the upper ends of the standard above the said stripper plate. ¹⁰

In testimony whereof I affix my signature.

WILLIAM SEABORN TEDDER. [L. S.]
